UNITED STATES PATENT OFFICE.

ALBERT ISKE, OF LANCASTER, PENNSYLVANIA, ASSIGNOR TO ISRAEL L. LANDIS, OF SAME PLACE.

COMBINED RAKE AND TEDDER.

SPECIFICATION forming part of Letters Patent No. 417,040, dated December 10, 1889.

Application filed September 16, 1889. Serial No. 324,115. (No model.)

To all whom it may concern:

Be it known that I, ALBERT ISKE, a citizen of the United States, residing at Lancaster, in the county of Lancaster and State of Pennsylvania, have invented certain new and useful Improvements in Combined Hay Rakes and Tedders, of which the following is a specification, reference being had therein to the accompanying drawings, in which—

10 Figure 1 represents a bottom view of my machine complete; Fig. 2, a vertical sectional view of the machine on the line $x\ x$ of Fig. 1; Fig. 3, a similar view on the line $x'\ x'$ of Fig. 1; Fig. 4, a detail sectional view of one of the 15 ratchet devices upon the ends of the tappet-shaft; Fig. 5, an elevation of the same; Fig. 6, a detail sectional view of one of the wheel-hubs, showing manner of securing spur-wheel thereto; Fig. 7, a detail view of one of the 20 separable sectional tappets; Fig. 8, a front elevation of a portion of the machine, showing more clearly the automatic dumping devices; Fig. 9, a detail sectional view of the clutch device on the tappet-shaft; Fig. 10, a detail 25 view of a portion of the endwise-movable hook-bearing rod and rear end of dumping-lever.

The invention has for its special object the improvement and the simplification of that 30 class of combined hay rakes and tedders covered by Letters Patent No. 398,165, granted February 19, 1889, to I. L. Landis (the assignee in this case) and myself, wherein the endwise-movable tappet-shaft and teeth-locking bar 35 are so arranged that by the manipulation of a single lever the driver may simultaneously shift them in opposite directions, and thereby convert the machine from a hay-rake into a tedder, and vice versa, without dismounting, as will be more fully hereinafter set forth.

The invention also has for objects the provision of extremely simple means for automatically dumping the machine, utilizing for this purpose the rotation of the tappet-shaft, 45 as will presently appear.

Another object I have in view is to provide means for insuring the operation of the teding devices whether the machine be turning to the right or left—a great desideratum with 50 this class of machines.

The invention has other minor objects in

view, which will appear in the course of this specification.

In the drawings annexed, a designates the main axle-beam mounted upon two transport-wheels b . Secured to the inner ends of the hubs of these wheels, by means of bolts or screws c , are two spur-wheels d , these wheels being held rigidly and prevented from turning independently of the wheels b by means 55 of lugs e , formed upon the hubs and fitting in recesses in the adjacent faces of the spur-wheels. Journaled in front and below the axle a , in suitable light metallic brackets f , is the hollow tappet-shaft g , having loosely journaled upon its ends the pinions h , which constantly engage the spur-wheels d , and are by the latter given rotation whenever the machine is drawn along. Secured upon the tappet-shaft adjacent to the inner faces of the 60 pinions h are two ratchet-wheels i . Pivoted upon the inner faces of the pinions h , and engaging with the teeth of the ratchet-wheels, are pawls j , which are actuated by springs k , secured to the pinions. By means of this 65 ratchet-and-pawl arrangement the tappet-shaft will be given rotation while the machine is moving forward, but will remain still while backing.

It will be observed that the teeth of the 80 spur-wheels on the hubs are considerably—say twice—wider than the teeth of the pinions, the object in this being to permit the endwise movement of the tappet-shaft without disengaging the wheels. This arrangement avoids a drawback experienced in former machines occasioned by entirely disengaging the pinion from the spur-wheel, inasmuch as it was often difficult to re-engage the wheels when it was again desired to convert the machine into a tedder, the teeth of the two wheels not always registering. It will also be observed that in this machine I employ two ratchet devices, one on each end of the tappet-shaft, whereas in all former machines 85 only one ratchet device was employed. The use of one was found to be impractical to a certain extent, inasmuch as the tappet-shaft would remain practically still while the machine was being turned in one direction, thereby leaving a portion of the hay untedded. 90 By placing two pinions and ratchets upon

the tappet-shaft this difficulty is entirely overcome, as the teding devices will continue to operate so long as either one of the transport-ing-wheels revolves.

5 Along the tappet-shaft at suitable intervals are clamped the tappets *l*, which are each constructed of two plates removably clamped over the said tappet-shaft by means of bolts. Thus making the tappets separable and re-10 movable enables me to readily renew any one of them, whenever worn or broken, without displacing or removing any of the remaining tappets or the shaft. Below and a little to the rear of the axle is journaled the rake-shaft *m*, suitable brackets *n* being attached to the axle for its support. Upon the rake-shaft are pivoted the oscillating rake-sections *o*, which are provided with the usual rear-15 wardly-projecting rake-teeth and the forwardly-projecting arms *p*, the latter being provided with rollers to receive the impact of the tappets. These rake-sections have a limited pivotal movement upon the rake-shaft by the means covered by the patent herein-20 before referred to. The brackets *n* are ex-25 tended out rearwardly and then curved upwardly and forwardly and bolted to the top of the axle, as shown. These brackets are thus utilized as supports for the clearer-bar *q*, which is bolted to them.

Supported in arms *r*, secured upon the ends of the rake-shaft, is an endwise-movable rod *s*, which reciprocates directly beneath the rake-teeth and is provided with hooks to engage therewith. This rod is operated or re-30 ciprocated by means of a lever *t*, pivoted in a bracket *u* upon the bottom of the axle, and provided at its rear end with a slot, through which passes a curved arm *v* upon the said 35 rod, the forward end of this lever being provided with a pin, which is constantly in engagement with a grooved collar *w* on the tappet-shaft. This lever *t* is shifted by means of a vertical pivoted lever *x*, which engages 40 its forward end, and is provided with a pivoted locking-hook *y*. By thus connecting the tappet-shaft and locking-rod by a pivoted lever it will be observed that the machine may be 45 converted from a rake to a tedder, and vice versa, by a single movement of a lever, the 50 shaft and locking-rod being moved in opposite directions synchronously. This part of the machine is fully described and covered in the former patent hereinbefore mentioned, 55 and a further description herein is deemed superfluous.

Bolted or clamped removably to the rake-shaft about midway its length is a horizontal dumping-arm *a'*, which is provided at its rear 60 end and upper side with a slot for the passage of the teeth-locking bar *s*. The bar *s* is provided with a slot *b*, through which passes a pin *c* upon the arm *a'*. This device permits the locking-rod to be moved endwise independently of the arm *a'*. The arm *a'* in front of the axle is provided with a vertical extension *d'*, which is connected by a link *e'*

to an operating-lever *f'*, which is pivoted upon the frame within easy reach of the driver's seat. By moving the lever *f'* in a backward direction the teeth may be elevated and the accumulated hay released. 70

For the purpose of automatically dumping the machine I have provided the following simple mechanism: Upon the tappet-shaft are 75 located two clutch-sleeves *g' h'*, the former being secured rigidly to the shaft, while the latter is allowed a limited sliding movement, a collar *k'* being provided for limiting its movement. The adjacent faces of these sleeves 80 are provided with ordinary clutch-teeth, and are normally held apart by means of an interposed spring *l'*. The sliding sleeve is operated by means of a rock-shaft *m'*, journaled in suitable bearings in the frame and provided with a depending arm *n'*, which is constantly in engagement with a groove in the clutch *h'*. The rock-shaft may be rocked by any suitable means; but I prefer to operate it by means of a foot-lever *p'*, which extends 85 up to within convenient reach of the driver. Formed integral with the sliding clutch-sleeve is a radial arm or tappet *q'*, which normally rests against a short pin *r'* in the rock-shaft *m'*. When the rock-shaft is partially 90 rotated by means of the foot-lever *p'*, the sliding clutch will be moved into engagement with the stationary clutch and the arm *q'* disengaged from its pin *r'*. Then, if the driver 95 holds the two clutch-sleeves into engagement, the rotation of the tappet-shaft will carry the arm *q'* around in the direction of the arrow shown in Fig. 2. As the arm *q'* revolves, it 100 will come in contact with the flanged roller *s'* on the forward end of the dumping-arm *a'* and force down the said forward end of the arm and elevate its rear end, thereby raising the rake-teeth a sufficient distance to release the gathered hay. As soon as the arm *q'* passes the roller *s'* the arm and rake-teeth will resume 105 their normal positions, and the driver may then remove his foot from the foot-lever and permit the interposed spring to separate the clutches. When the clutches become disengaged after dumping, the friction between 110 the sliding sleeve and its shaft will be sufficient to carry the arm *q'* around until it rests upon the pin *r'*—its normal position.

In order that the rake-teeth may not drop too suddenly and be thereby injured, I may 115 provide the end of the arm *q'* with an upward extension *t'*, against which will impinge the flanged roller *s'* as the rake-teeth resume their normal position.

It will be observed that if the extension *t'* 120 were not employed, as soon as the roller *s'* reached the end of the arm *q'*, it would leave it suddenly and permit the rake-teeth to fall violently to the ground; but by employing this extension and inclining it slightly rear-125 ward the momentum of the falling teeth is interrupted or retarded for a short distance by the roller *s'* impinging against this extension, thereby breaking the force of the fall of 130

the teeth. Flanging the roller s' prevents the arm q' slipping off the side of the roller during operation. It will also be observed that by using pinions and ratchets on both ends 5 of the tappet-shaft all "side draft" while dumping with foot-lever is avoided.

Having thus fully described my invention, what I claim, and desire to secure by Letters Patent, is—

- 10 1. The combination, in a combined hay rake and tedder, of a frame, transporting-wheels provided on the inner ends of their hubs with spur-wheels d , the rake-shaft, pivoted rake-sections provided with forwardly-extending arms p , the tappet-shaft journaled in bearings in front of the rake-sections and provided with tappets, loose pinions journaled upon the ends of this shaft and held in constant engagement with the spur-wheels d , 15 these pinions being provided with teeth narrower than the teeth of the spur-wheel ratchet-and-pawl mechanism upon the tappet-shaft adjacent to the said loose pinions, and means for shifting the tappet-shaft endwise, 20 substantially as described.
- 25 2. The combination of the frame and transporting-wheels, the rake-shaft and rake-sections, the horizontal dumping-arm a' , secured to the rake-shaft and provided with a roller, the tappet-shaft, the stationary and sliding clutch-sleeves thereon, the sliding clutch-sleeve being provided with a radial arm, and

means for holding the two clutch-sleeves in engagement, as and for the purpose described.

3. The combination of a frame mounted 35 upon transporting-wheels, the rake-shaft and rake-sections, a tappet-shaft, stationary and sliding clutches upon the tappet-shaft, a spring interposed between the clutches, a radial arm carried by the sliding clutch, means 40 for holding the sliding clutch into engagement with the stationary clutch, and a dumping-arm a' , secured to the rake-shaft and provided upon its forward end with a flanged roller, as and for the purpose described. 45

4. The combination of a frame mounted upon wheels, a rake-shaft provided with rake-sections, an arm a' , secured to the rake-shaft and provided with a roller s' , stationary and sliding clutches upon a rotating shaft journaled in front of the rake-shaft, a rock-shaft 50 journaled in the frame and provided with an arm n' , which engages the said sliding clutch, means for operating the rock-shaft, and a radial arm on the sliding clutch adapted to rest 55 normally on a pin in the rock-shaft, as described.

In testimony whereof I affix my signature in presence of two witnesses.

ALBERT ISKE.
